United States Patent Office

Des. 185,232
Patented May 19, 1959

185,232

BABY VEHICLE

Raymond G. Pierson, Jr., Gardner, Mass., assignor to
Hedstrom Union Company, Fitchburg, Mass.

Application February 8, 1957, Serial No. 44,806

Term of patent 7 years

(Cl. D14—14)

Fig. 1 is a side elevation of a baby vehicle embodying my new design, the opposite side of the vehicle being substantially identical;

Fig. 2 is a top plan view thereof; and

Fig. 3 is a fragmentary front elevation thereof.

I claim:

The ornamental design for a baby vehicle, as shown.
